UNITED STATES PATENT OFFICE

CHARLES P. MULLEN, OF CONSHOHOCKEN, PENNSYLVANIA

EAVES-TROUGH HANGER

Application filed August 29, 1928. Serial No. 302,864.

The invention relates to improvements in hangers for eaves troughs, of the general type shown in my U. S. application, Serial No. 222,606, filed September 28, 1927. Like the device of this pending application, the present hanger embodies a stationary vertical bar for anchorage to a roof, and an eaves trough support adjustably connected with said bar, the adjustable connection being such that said support snaps into interlocking engagement with the bar when adjusted to the desired position.

It is the principal object of the present invention to provide a hanger of the type above mentioned, which is generally simplified and improved, producing an article which may be rather inexpensively manufactured, yet will be efficient and durable.

In carrying out the above end, a further object is to provide a construction which may be formed of metal stampings for convenience of manufacture, said construction however being such as to possess the requisite rigidity.

A still further aim is to provide unique means for securing the eaves trough to the support and holding it in place under spring action so that it cannot move for instance under the action of wind, causing undesirable noise.

With the foregoing in view, the invention resides in the novel subject matter hereinafter described and claimed, description being accomplished by reference to the accompanying drawings.

Fig. 1 is a side elevation of the hanger illustrating the eaves trough in vertical section.

Fig. 2 is a front elevation of the parts shown in Fig. 1.

Fig. 3 is a fragmentary rear elevation looking in the direction indicated by the arrow A of Fig. 1.

Fig. 4 is a view similar to Fig. 3 but illustrating the manner in which the trough support is turned with respect to the bar for connection to or disengagement from said bar.

Figs. 5, 6 and 7 are horizontal sectional views on the correspondingly numbered lines of Fig. 3.

Fig. 8 is a similar view on line 8—8 of Fig. 4.

Figs. 9 and 10 are fragmentary perspective views showing details hereinafter described.

Fig. 11 is a fragmentary side elevation showing a modified form of construction.

Fig. 12 is a vertical sectional view on line 12—12 of Fig. 11.

Fig. 13 is a rear elevation as indicated by the arrow B of Fig. 11.

Fig. 14 is a horizontal sectional view on line 14—14 of Fig. 11.

The details of construction selected for illustration in the present application, will be specifically described, with the understanding that within the scope of the invention as claimed, variations may be made.

The construction illustrated in Figs. 1 to 10 will first be described and the differences which the other form of construction possesses, will then be pointed out.

15 denotes a vertical channel metal bar having an angular upper end 16 for anchorage to a roof, said bar being formed with a longitudinal slot 17 and with longitudinally spaced teeth 18 along at least one and preferably both edges of the slot. The bar 15 is of resilient metal and the slot 17 provides this bar with parallel longitudinal side members 19 capable of springing for a purpose hereinafter set forth, each member in the present disclosure being provided with a row of teeth 18. An eaves trough support 20 is adjustably engaged with the bar 15 and is of novel construction hereinafter described. This support is shaped to lie tightly against the bottom of the eaves trough 21, and the latter is held tightly in place by a spring metal hook 22 hereinafter more fully described. The support 20 is preferably of the detailed construction shown and described below.

Two curved metal strips 23 are secured side by side by spot welding or the like 24, the curved upper edges of these strips being laterally bent at 25 to provide reinforcing flanges. At their inner and outer portions, the strips are shaped to provide forwardly and downwardly projecting hooks 26—27, and the upper edge of the former is preferably provided with lateral reinforcing 100

flanges 28. The inner edge of the eaves trough 21 engages the hook 26, the usual front bead 29 of said eaves trough overlies the hook 27, and the spring metal hook 22 is engaged with said hook 27 and snapped over the bead 29. This hook 22 exerts a constant downward pull upon the bead 29, tending to transversely slide the trough 21 to hold its inner edge tightly engaged with hook 26, so that loose movement and rattling of the trough are prevented. Hook 22 is preferably formed from a metal strip bent as shown and formed with an opening 30 to receive the hook 27.

The strips 23 are provided with straight vertical rear or inner ends having flanges 31 which are bent laterally in opposite directions, providing a flat vertical plate-like portion adapted to lie against the front side of the bar 15. The outer portions of these flanges are rearwardly bent, providing additional flanges 32 for disposition at the outer sides of the side members 19. Near the upper ends of the flanges 31, the strips 23 are provided with rearwardly projecting T-shaped lugs 33 whose shanks are secured together and jointly form a two-ply shank 34 for rearward passage through the slot 17. The heads of these lugs 33 are bent substantially upon themselves to provide a head 35 to contact pivotally and slidably with the rear side of the bar 15. The relation of this head with the bar, the manner of engaging it with or disengaging it from said bar, and the specific manner of forming the head, are illustrated more particularly in Figs. 5, 4 and 9 respectively.

Near the lower ends of the flanges 31, the strips 23 are provided with rearwardly projecting L-shaped lugs 36. Two reaches of these lugs are secured side by side to provide an additional two-ply shank 37 for rearward passage through the slot 17. The other reaches of the lugs 36 are bent laterally in opposite directions to provide a horizontal lug 38 which is shaped to momentarily spring the side members 19 apart and then snap into interlocking engagement with them, when said lug is rearwardly forced in the slot 17. This lug is receivable between the teeth 18 and hence the support 20 may be vertically adjusted to any desired extent upon the bar 15 and then locked in desired relation with the latter.

When initially engaging the support 20 with the bar 15 or when disengaging the two, they are relatively moved to the relation shown in Fig. 4, in which relation head 35 may readily pass through the slot 17. Righting the parts then moves them into such relation as to dispose the head 35 behind the bar 15 and transversely of the latter as shown for instance in Figs. 3 and 5. The T-head formed by the parts 34-35, now slidably engages the bar 15 and also permits vertical

pivotal movement of the eaves trough support 20. In order to vertically adjust the support, it is necessary that the lug 38 shall clear the teeth 18, and this is permitted by upward swinging of said support about the T-head as a pivot. When the desired adjustment has been made, support 20 is again tilted downwardly, during which movement the lug 38 enters between the teeth 18, momentarily springs the side members 19 outwardly, and then snaps into interlocking engagement with these members. Hence, support 20 is tenaciously held in adjusted position upon the bar 15, and the construction is such that no bolts or analogous fasteners are necessary, permitting adjustments to be made rapidly and with ease.

In the construction shown in Figs. 11 to 14, the eaves trough support 20^a may be considered as a duplicate of the support 20, with the exception that its rearwardly projecting flanges 32^a are provided with inwardly stamped detents 32^b. The bar 15^a is provided with a longitudinal slot 17^a to receive the lug 38, but instead of providing this bar with teeth along opposite edges of the slot, its spring metal side members 19^a are formed with slots 18^a for engagement with the detents 32^b. Lug 38 snaps into the slot 17^a in the same manner as lug 38 engages slot 17, and as the support 20^a moves to its final adjusted position, the detents 32^b enter the slots 18^a through the open front ends of the latter.

The construction shown and described is simple and inexpensive, may be easily and advantageously manufactured, may be marketed at a reasonable cost and will be generally desirable and efficient. On account of the existing advantages for the details disclosed, they are preferably followed. Attention is again drawn to the fact however that within the scope of the invention as claimed, variations may be made.

I claim:

1. An eaves trough hanger comprising a stationary resilient vertical bar having a longitudinal slot providing it with two parallel side members, a trough-supporting member having a portion abutting the front side of said bar and provided with parallel vertical flanges straddling said bar, a lug on said trough-supporting member adapted to enter said slot, momentarily spring said side members apart and then snap into engagement with said side members, and bar-engaging means on said trough-supporting member above said lug, said means slidably and pivotally engaging said bar.

2. An eaves trough hanger comprising a stationary resilient vertical bar having a longitudinal slot providing it with two parallel side members, a trough-supporting member having a portion abutting the front side of said bar and provided with parallel vertical

flanges straddling said bar, a lug on said trough-supporting member adapted to enter said slot, momentarily spring said side members apart and then snap into engagement with said side members, and a T-head on said trough-supporting member above said lug, the shank of the T passing slidably through said slot and the head of the T being in slid-
5 able and pivotal contact with the rear side of
10 said bar.

3. An eaves trough hanger comprising a stationary vertical resilient bar having a longitudinal slot providing it with resilient side members, the inner edge of at least one of said 15 side members being provided with longitudinally spaced teeth, a trough-supporting member having means slidably and pivotally en-
gaging said bar, and a lug on said trough-
supporting member below said means adapt-
20 ed to enter said slot and engage said teeth, said lug being shaped to momentarily spring the aforesaid side members apart and to then snap into interlocking engagement therewith.

25 4. An eaves trough hanger comprising a stationary vertical resilient bar having a longitudinal slot providing it with resilient side members, the inner edge of at least one of said 30 side members being provided with longitudinally spaced teeth, a trough-supporting member having a T-head, the shank of the T pass-
ing slidably through said slot and the head of the T being in pivotal and slidable contact with the rear side of said bar, and a lug on
35 said trough-engaging member below said T-
head adapted to enter said slot and engage said teeth, said lug being shaped to momen-
tarily spring the aforesaid side members apart and to then snap into interlocking en-
40 gagement therewith.

5. In an eaves trough support, a trough-
supporting member having a vertical trans-
verse plate-like portion at its rear end to con-
tact with the front side of a vertical slotted
45 bar, a T-head projecting rearwardly from
said member to slidably and pivotally engage
the slotted bar, and a lug projecting rear-
wardly from said member to snap into the bar
slot, the lug being below the T-head.

50 6. In an eaves trough hanger, two metal
strips secured side by side to support an eaves
trough, the rear ends of said strips each hav-
ing a T-shaped lug, the shanks of said lugs
projecting rearwardly side by side to provide
55 a two-ply shank, the heads of said lugs being
folded substantially upon themselves to pro-
vide a head transverse to said two-ply shank,
said two-ply shank and its head being adapt-
ed for engagement with a vertical slotted bar,
60 said rear ends of said strips having bar-en-
gaging means below said shank and head.

65 7. In an eaves trough hanger, two metal
strips secured side by side to support an
eaves trough, the rear ends of said strips be-
ing provided with L-shaped lugs, two reaches

of said lugs jointly forming a rearwardly
projecting shank, the other reaches being
bent laterally in opposite directions from said
shank and jointly forming a lug adapted to
snap into a slot of a vertical bar, said rear
ends of said strips being provided above said
shank and lug with means to slidably engage
the vertical bar.

8. In an eaves trough hanger, two metal
strips secured side by side to support an eaves
trough, the rear ends of said strips having
vertical flanges bent laterally in opposite di-
rections and then bent rearwardly in parallel
relation, providing a channel to receive a
vertical bar, said strips having means to en-
gage the bar and retain the channel in proper
position thereon.

9. In an eaves trough hanger, two metal
strips secured side by side to support an eaves
trough, said strips having vertical rear edges
and vertical flanges projecting oppositely
therefrom to abut the front side of a vertical-
ly slotted bar; said rear edges being provided
at their upper portions with rearwardly pro-
jecting T-shaped lugs whose shanks jointly
form a two-ply shank for passage through
the bar slot, the heads of said lugs being
folded substantially upon themselves to form
a head to contact with the rear side of the
bar; the lower portions of said rear ends of
the strips being provided with L-shaped lugs
two reaches of which jointly form a second
shank for passage through the bar slot, the
other reaches of said L-shaped lugs being bent
laterally in opposite directions and jointly
forming a lug adapted to snap into the bar
slot.

In testimony whereof I have hereunto af-
fixed my signature.

CHARLES P. MULLEN.
